The ornamental design for an air compressor pump as shown and described.

DESCRIPTION

FIG. 1 is perspective view of air compressor pump according to our new design, with a part being encircled by a dashed line and marked by “9”, indicating the part corresponding to FIG. 9;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlargement of a part of FIG. 1.

The shade lines in the Figures show contour and not surface ornamentation.

The dash-dot-dash broken lines encircling portions of the claimed design in FIGS. 1 and 9 are used to illustrate part of FIG. 1 in an enlargement view in FIG. 9; such lines themselves form no part of the claimed design.

The dash broken lines indicate portions of the air compressor pump that form no part of the claimed design.
